UNITED STATES PATENT OFFICE.

JOHN N. LEACH, OF MELROSE, MASSACHUSETTS, ASSIGNOR, BY DIRECT AND MESNE ASSIGNMENTS; TO NATIONAL OIL HEATING COMPANY, A CORPORATION OF MAINE.

APPARATUS FOR GENERATING AND BURNING GASES FROM HYDROCARBONS.

SPECIFICATION forming part of Letters Patent No. 783,872, dated February 28, 1905.

Application filed October 22, 1902. Serial No. 128,254.

To all whom it may concern:

Be it known that I, JOHN N. LEACH, a citizen of the United States, residing at Melrose, in the county of Middlesex and State of Massachusetts; have invented certain new and useful Improvements in Apparatus for Generating and Burning Gases from Hydrocarbons, of which the following is a specification, reference being had therein to the accompanying drawings, which form a part thereof.

My invention relates to an apparatus for generating and burning gases from hydrocarbons, and more particularly to a class of burners especially adapted for heating purposes and to use kerosene, crude oil, or other hydrocarbons.

The object of my invention is to provide an apparatus for generating and burning gases from hydrocarbons wherein the kerosene or other oil will be effectively volatilized and mixed with oxygen before its introduction within the combustion-chamber.

A further object is to provide an apparatus of this class wherein the flame may be readily controlled—that is, capable of being reduced or extinguished, increased, or relighted at any time—and wherein the volatilization of the fuel-oil when interrupted may be resumed without the necessity of manual ignition to start such renewed volatilization.

A still further object is to provide an apparatus of this class which will be automatically lighted and relighted.

A still further object is to provide an apparatus of this class wherein the vaporizing of the oil will not be dependent upon boiler heat under any conditions.

A still further object is to provide an apparatus of this class wherein the dangers of back firing from the combustion to the mixing chamber will be reduced to a minimum, if not entirely obviated; and a still further object is to provide an apparatus of this class wherein the supply fuel may be used under high pressure to force the flame when desired and also capable of convenient regulation.

The invention consists in combining with a burner a vaporizer comprising a vaporizing

coil and a superheating-coil formed of a continuous pipe wherein the fuel-oil is subjected to successive flames, whereby the oil is vaporized and the vapor is superheated before being thoroughly mixed with oxygen and introduced within the combustion-chamber.

It further consists in the utilization of an auxiliary burner having a permanent flame the combustion-chamber of which is either a part of or in direct communication with the combustion-chamber of the heating-burner; and it consists, still further, in those novel features of construction and arrangement of parts hereinafter set forth and described, and more particularly pointed out in the claims hereto appended.

Referring to the drawings, Figure 1 is a sectional elevation of my burner as applied to the boiler of a steam-carriage. Fig. 2 is a plan thereof, also showing the detached controlling-valve, the top plate of the combustion-chamber being removed. Fig. 3 is a front elevation of said controlling-valve as applied to the chauffeur's seat of a steam-carriage, so as to be readily accessible. Fig. 4 is a side elevation of a modification of the invention as applied to a heating-furnace, partly broken away and partly in section. Fig. 5 is a horizontal section on the line 5 5 of Fig. 4. Fig. 6 is a front vertical section in perspective of the lower part of a heater, showing the primary and the secondary burners each in section and also disclosing a modified form of burner-plate. Fig. 7 is a horizontal section on line 7 7 of Fig. 4, showing a modified form of burner-plate. Fig. 8 is a detail view of the mixing-tube and the air-inlet tube with the upper portion of the needle-point valve of the tube in section. Fig. 9 is a detail view of the lower portion of the said needle-point valve in section, and Fig. 10 is a horizontal section taken on the line 10 10 of Fig. 6.

Like letters refer to like parts throughout the several views.

In Figs. 1 to 3 of the drawings I have shown the apparatus as used in connection with the boiler of a steam-carriage and in Figs. 4 to 10, inclusive, as used in connection with a

heating furnace; but as its utility or efficiency is not affected or influenced in any way by its relation I do not desire to be understood as limiting the invention to a construction applicable only to such uses.

My burner comprises an inclosing casing, as *a*, which is divided into separate mixing-chambers *d* and *e*, each provided with an individual burner-plate, as *b* and *c*, and into a combustion-chamber *f*, extending over and common to both burners. For convenience burner *c* will hereinafter be designated the "primary" burner and burner *b* the "secondary" burner. A top plate or plates, as *g*, Figs. 4 to 6, and 8, Fig. 1, are provided for the entire combustion-chamber *f*. To prevent interference between the secondary burner and the flame of the primary burner, I so divide the combustion-chamber *f*, adjacent to the latter as to have the different portions of said combustion-chamber in communication only at a point some distance above the burner *c* and provide an imperforate top plate *g'* or a hood, as *g''*, Figs. 4 and 5, directly above the primary burner to confine the flame, thus preventing the extinguishment of the flame of this burner from back draft due to the ignition of the secondary burner therefrom.

The oil, whether kerosene, crude oil, or other hydrocarbon is used, is stored in a detached tank (not shown) and is fed to the secondary burner through a pipe *i*, which is passed into the combustion-chamber *f* and formed into a vaporizing-coil *i'* directly above the secondary burner *b*, thence through said chamber to directly above the primary burner *c*, where a second such coil, constituting a superheating-coil *i''*, is formed, of a size to best expose all parts thereof to the action of the primary flame or torch, and thence to the mixing-chamber *d*, where it terminates in a spraying-nozzle *i'''*, controlled by a needle-point valve *i''*. It will be observed that the vaporizer, comprising the vaporizing-coil *i'* and superheating-coil *i''* and the portions of pipe connecting these coils, all contained within the combustion-chamber *f*, feeds the secondary burner *b* only.

A separate system of piping, as *k*, which may take its oil from the same tank as pipe *i* or from a separate tank, feeds the primary burner *c*. This piping *k* is passed vertically through the mixing-chamber *e* and the coil *i''* to the mixing-tube *l*, which is in direct communication with the air through the inlet *l'* and with the mixing-chamber *e*. The portion of it within the mixing-chamber *e* is incased to prevent back firing, and the upper portion thereof, constituting the primary-burner vaporizer, is fully exposed to the flame within the combustion-chamber directly above the primary burner *c*.

The burner *b* is preferably formed of corrugated metal the upper ridges of which are provided with slots *b'*, *b''*, &c., spaced about

one-half to three-fourths of an inch apart. This construction is found simple to make and effective in practice, but it is apparent that other arrangements of burner-openings may be adopted in combination with the other parts 70 of my apparatus without departing from the scope of my invention. It has been found, however, that in burners employing thin or sheet-metal burner-plates the danger from back firing from the combustion to the mixing chamber is great when said plates become overheated or reach a red heat. This danger is obviated by providing the burner *b* with a facing of asbestos or other material non-conductive of heat, as *b'''*, on either the top or the bottom thereof, or both, in the spaces between the slots *b'* and the separate tiers of said slots. This has been found to practically eliminate this danger of back firing from this source, no conditions having developed wherein such 85 takes place.

Preferably the primary burner *c* is of thin iron casting having small burner-holes drilled therein, as *c'*, *c''*, &c., and a firing-pan *c''*, formed on the upper face thereof contiguous to and surrounding the feed-pipe *k*, which pan is designed to hold the alcohol necessary to the initial formation of vapor and the ignition of this burner. The form of burner shown has proved effective in use; but other forms can 95 be used, if desired.

Adjacent to the burner *c* I provide a needle-point valve *k'*, the stem *k''* of which passes through the vaporizer portion of the pipe *k*, which is used to regulate the feed of oil through the pipe *k*. This pipe is vertically disposed to prevent clogging of this valve.

In using my apparatus the oil may be fed thereto by gravity alone, or the oil in the main tank may be placed under pressure in any 105 well-known or desired manner to enable the forcing of the flame. Whatever the system used, I place in the length of the pipe *i* at some 110 convenient point a needle-point valve *n*, by means of which the flow of oil to the secondary burner *b* may be controlled or entirely shut off, if desired.

The construction and arrangement heretofore described are common to all forms of my invention, and the different applications thereof entail merely immaterial variations in the relation of these parts and other details of construction necessary to their use in a definite connection.

In Figs. 1 to 3, inclusive, I have shown the 120 apparatus as applied to a steam-carriage boiler, as above stated. When so used, the primary burner *c*, its mixing-chamber *e*, and its portion of the combustion-chamber *f* are arranged at one side of the secondary burner 125 *b*, so that the latter alone will be beneath the boiler. This is preferable, as by such arrangement the secondary burner constitutes the sole source of heat for generating steam, and the permanent flame of the primary 130

burner will not raise the pressure in the boiler, but has been found to maintain a certain pressure somewhat lower than the blow-off point. In this construction the plate g of Figs. 4 and 6 is dispensed with, the lower crown-sheets of the boiler taking its place. In this form of my invention the combustion-chamber f is divided adjacent to the burner c by a vertical partition h , extending to about one-half the height of the combustion-chamber, thus protecting the flame of this burner from the effects of the back draft occasioned when the secondary burner is ignited, still having all portions of the combustion-chamber, however, in direct communication with each other. g is a plate located over the primary burner, and it is imperforate to confine the flame and deflect it more or less over the secondary burner. When used in this connection, the valve n is mounted on a transverse plank located directly beneath the chauffeur's seat, as o , so that the secondary-burner flame may be reduced, increased, extinguished, or relighted, as desired, from a point convenient to the throttle-lever.

In Figs. 4 to 10, inclusive, the invention is shown as applied to the ordinary heating-furnace. The apparatus is here placed beneath an air-chamber p of any desired design and arrangement, which is provided with the usual hot-air-distributing pipes p' and the flue-pipe p'' to exhaust the gases which may enter the chamber p . The apparatus is suspended within the base of the furnace, as the ordinary fire-pot, by means of the flange a' , and an additional support therefor is provided, as the standard a'' , within the ordinary ash-pit p^3 . To prevent as much as possible the radiation of heat, the casing a above the burner b and c is protected by a sheathing of asbestos, fire-brick, or other similar material a^3 . The pit p^3 constitutes a fresh-air chamber with which the mixing-tube j and the air-inlet l' of the mixing-tube l are in communication and draw their supply of air. For convenience in this type of apparatus the primary burner c is arranged within the secondary burner b instead of at one side thereof, and the mixing-chamber e and burner-plate c are arranged below the level of the secondary burner b , thus dispensing with the partition h of Figs. 1 and 2, yet protecting the flame of this burner from the effects of back draft. The hood g^2 , arranged above the burner c , serves to confine the flame of this burner and aids in so protecting it. The top plate g in this form of burner is provided with a plurality of small openings, which enables this plate to act as a deflector to confine the flame of the secondary burner more or less within the combustion-chamber to insure more perfect combustion and avoid contamination of the air within the chamber p by the unconsumed gases and to deflect the vapor into that part

of the combustion-chamber over the primary 65 burner, so as to insure ignition.

The corrugations of the burner b may take any desired form. In Figs. 1 to 5, inclusive, they are shown in a plurality of parallel concentric circles and in Figs. 6 and 7 in straight 70 parallel lines.

The operation of the heretofore-described apparatus whatever its application, is in so far as I have been able to determine as follows: To ignite the apparatus, a small amount of 75 alcohol is placed in the pan c^2 and ignited and the needle-point valve l' opened after the vaporizer portion l^2 has been sufficiently heated, the sufficiency of heat being ascertained by the color of the flame and the perfection of 80 the combustion in the primary burner. As the oil passes through the portion of the pipe k adjacent to said pan the heat and flame therefrom and the already-heated pipe vaporize it, and in this state it is charged into the 85 mixing-tube l , where it receives an effective admixture of oxygen through the air-inlet l' . Through the tube l it passes to the mixing-chamber e and from there to the combustion-chamber f , through the openings $c' c'$ 90 in the primary burner c , where it becomes ignited from the flame of the alcohol. The quantity of the alcohol being small, its flame soon dies down, so that the volatilization of the oil passing through pipe k is continued 95 solely by means of the flame from the primary burner c , the flame of which from this source is thus rendered self-sustaining and permanent. When it is desired to light the secondary burner, the needle-point valve n is opened 100 to permit the passage of oil to the vaporizer through pipe l . This initial charge by contact with the superheating-coil l^2 , which is kept hot by the flame from the primary burner c , is converted into a vapor more or less superheated, which passes through the nozzle l^3 and mixing-tube j , where it receives an admixture of oxygen, to the mixing-chamber d . From this chamber it passes through the slots 105 $b' b''$ in the secondary burner b to the combustion-chamber f . The accumulation of this vapor or gas in the combustion-chamber f , it is apparent, is self-ignited from the primary burner c . The flame thus produced is at first a blue-vapor flame of apparent good combustion, but after the vaporizing-coil becomes a dull cherry-red color changes into a nearly transparent flame of more perfect combustion. This flame acts directly upon the vaporizing-coil l^2 and thereafter vaporizes the oil at this 110 point, such vapor being afterward passed through the superheating-coil l^2 , where it is superheated by the primary burner, and through the mixing-tube j to the secondary burner b . The fuel-oil is therefore subjected 115 while in the vaporizer to the continuous heat and successively to the flames of said secondary and said primary burner. When so passed

120

125

through the two coils, as above stated, a pure hydrocarbon gas is generated, which when mixed with oxygen, the admixture of which is regulated by means of the needle-point valve z , develops an intense heat with a small expenditure of liquid fuel. With the ignition of the secondary burner b from the primary burner c a back draft is created, which tends to extinguish the flame of the latter. The partition h in the form shown in Figs. 1 to 3 and the arrangement of the burner c on a lower level than the secondary burner b , as shown in Figs. 4 to 7, inclusive, thus having the point of communication between the portion of the combustion-chamber, adjacent to said primary burner some distance above said burner and the imperforate plate or hood to confine its flame, serves to protect this flame from the effects of this back draft.

The intense heat in the combustion-chamber f has heretofore been found to overheat the burner-plates when thin metal was used for the same to an extent which induced back firing to the mixing-chamber, with its resulting inconvenience and injury. The non-conductive facing b^2 has been found to quite effectively prevent this overheating and the results therefrom.

The volume of flame is controlled by means of the valve n and may therefore be readily regulated from any convenient point where this valve is located. If it be desired to extinguish the flame entirely, this may be done by means of this valve, and the burner b may be relighted and the flame again produced to the desired extent by simply opening this valve, as the closing of the valve does not affect the primary-burner flame in any way, these burners being supplied from separate fuel-supply-pipe systems. It has been found that the fire can be forced to any desired extent without adversely affecting combustion or injuring the burner in any way.

The application of my burner to a heating-furnace results in the production of an efficient, clean, and economical means of heating and such as can be readily regulated.

It is not my intention to limit the invention to the details of construction as herein shown and described, as it is apparent that the burner may be varied without departing from the spirit and scope of my invention.

Having described the invention, what I claim as new, and desire to have protected by Letters Patent, is—

1. In an apparatus for generating and burning gases from hydrocarbons, the combination of a primary burner and a secondary burner provided with separate mixing-chambers, a secondary-burner fuel-supply system comprising a vaporizer and a superheater formed of a continuous pipe and subjected respectively directly to the flame of said secondary burner and said primary burner, means whereby oil is fed to said vaporizer and means whereby

vapor from said superheater is given an admixture of air and discharged into said secondary-burner mixing-chamber; a primary-burner fuel-supply system comprising an individual vaporizer, means whereby oil is fed thereto, and means whereby vapor from said vaporizer is given an admixture of air and discharged into the mixing-chamber of said primary burner.

2. In an apparatus for generating and burning gases from hydrocarbons, the combination of a primary burner, and a secondary burner provided with separate mixing-chambers, a primary-burner fuel-supply system comprising a vaporizer so disposed as to be subjected to the flame of said primary burner, means whereby oil is fed to said vaporizer and means whereby vapor from said vaporizer is given an admixture of air and discharged into said primary-burner mixing-chamber, a secondary-burner vaporizer so disposed as to subject portions thereof to the flames of each of said burners, means whereby oil is fed to said secondary-burner vaporizer and means whereby vapor from said secondary-burner vaporizer is given an admixture of air and discharged into said secondary-burner mixing-chamber.

3. In an apparatus for generating and burning gases from hydrocarbons, the combination of a primary burner and a secondary burner provided with separate mixing-chambers and separate mixing-tubes providing independent communication between each mixing-chamber and the atmosphere, a primary-burner fuel-supply system comprising a vaporizer so disposed as to be subjected to the flame of said primary burner, means whereby oil is fed to said vaporizer and means whereby vapor from said vaporizer is discharged into the mixing-tube of said primary-burner mixing-chamber to give said vapor an admixture of air, a secondary-burner vaporizer so disposed as to subject portions thereof to the flames of each of said burners, means whereby oil is fed to said secondary-burner vaporizer and means whereby vapor from said secondary-burner vaporizer is discharged into the mixing-tube of said secondary-burner mixing-chamber to give it an admixture of air.

4. In an apparatus for generating and burning gases from hydrocarbons, the combination of a primary burner, and a secondary burner provided with separate mixing-chambers and having a common combustion-chamber, independent fuel-supply systems therefor comprising respectively a vaporizer wherein fuel-oil is subjected to the flame of the primary burner and a vaporizer wherein the fuel-oil is subjected successively to the flames of both said burners and connections providing communication between said vaporizers respectively and a source of oil-supply, and the mixing-chambers of the respective burners.

5. In an apparatus for generating and burning gases from hydrocarbons, the combination

of a primary burner and a secondary burner provided with separate mixing-chambers and having a common combustion-chamber, independent fuel-supply systems therefor comprising respectively a vaporizer wherein fuel-oil is subjected to the flame of the primary burner and a vaporizer wherein the fuel-oil is subjected successively to the flames of both said burners, connections providing communication between said vaporizers respectively and a source of oil-supply, and the mixing-chambers of the respective burners, and a fire-pan adjacent to said primary burner wherein a temporary flame is produced to produce the initial charge for said primary burner.

6. In an apparatus for generating and burning gases from hydrocarbons, the combination of a primary burner and a secondary burner provided with separate mixing-chambers and having a common combustion-chamber, independent fuel-supply systems therefor comprising respectively a vaporizer wherein the fuel-oil is subjected to the flame of the primary burner, and a vaporizer wherein the fuel-oil is subjected successively to the flames of both said burners, connections providing communication between said vaporizers respectively and a source of oil-supply, and the mixing-chambers of the respective burners, and means whereby extinguishment of the flame of the primary burner from the back draft from the ignition of the secondary burner is prevented.

7. In an apparatus for generating and burning gases from hydrocarbons, the combination of a primary burner and a secondary burner provided with separate mixing-chambers and having a common combustion-chamber, independent fuel-supply systems for said burners, and a top plate over said primary burner, that portion of the combustion-chamber between said burner and said plate being in communication with the rest of the said combustion-chamber at a point above said burner and adjacent to said plate.

45 8. In an apparatus for generating and burning gases from hydrocarbons, the combination of a primary burner and a secondary burner provided with separate mixing-chambers and having a common combustion-chamber, independent fuel-supply systems therefor and a partition dividing the lower portion of said combustion-chamber adjacent to said primary burner from the rest of the lower portion of the said combustion-chamber.

55 9. In an apparatus for generating and burning gases from hydrocarbons, the combination of a primary burner and a secondary burner provided with separate mixing-chambers and having a common combustion-chamber, independent fuel-supply systems therefor comprising respectively a vaporizer wherein fuel-oil is subjected to the flame of said primary burner and a vaporizer wherein the fuel-oil is subjected successively to the flames of both said burners, connections providing communication

between said vaporizers respectively and a source of oil-supply, and the mixing-chambers of the respective burners, and means whereby the fuel-supply for said secondary burner may be controlled independently of that for the said primary burner.

5 10. In an apparatus for generating and burning gases from hydrocarbons, the combination of a primary burner and a secondary burner provided with separate mixing-chambers and having a common combustion-chamber, independent fuel-supply systems therefor comprising respectively a vaporizer wherein fuel-oil is subjected to the flame of the primary burner, and a vaporizer wherein the fuel-oil is subjected successively to the flames of both said burners, connections providing communication between said vaporizers respectively and a source of oil-supply, and the mixing-chambers of the respective burners and a valve arranged at a point of said secondary-burner fuel-supply system remote from said burner whereby the flame of said burner may be controlled independently of said primary-burner flame.

90 11. In an apparatus for generating and burning gases from hydrocarbons, the combination of a primary burner and a secondary burner provided with separate mixing-chambers and having a common combustion-chamber, a secondary-burner fuel-supply system comprising a vaporizer and a superheater formed of a continuous pipe and subjected respectively to the flame of said secondary burner and said primary burner, connections providing communication between said vaporizer and a source of oil-supply and between said superheater and the mixing-chamber of said secondary burner, a primary-burner fuel-supply system comprising an individual vaporizer, means for feeding oil thereto, means whereby vapor therefrom is given an admixture of air and discharged into the mixing-chamber of said primary burner, and a fire-pan arranged to produce an initial supply of vapor to said primary burner.

100 12. In an apparatus for generating and burning gases from hydrocarbons, the combination of an inclosing casing, means dividing said casing into separate mixing-chambers, an individual burner-plate having burner-openings therein extending over said mixing-chambers respectively whereby a combustion-chamber common to, and above both said chambers is provided, said burner-plates closing the bottom of said combustion-chamber, and, through the said burner-openings, establishing communication between said mixing-chambers and said combustion-chamber, independent fuel-supply systems for said burner-plates respectively comprising a vaporizer disposed above both said burner-plates whereby fuel-oil therein is subjected successively to the flames thereof, and a vaporizer wherein fuel-oil is subjected to the flame of but one of said burner-

plates, mixing-tubes providing communication between said mixing-chambers respectively and the atmosphere, connections providing communication between each of said vaporizers and a source of oil-supply, discharging vapors therefrom into said mixing-chambers respectively through said mixing-tubes, and means whereby the fuel-supply for each said burner-plate is controlled independently of the other.

13. In an apparatus for generating and burning gases from hydrocarbons, the combination of an inclosing casing, means dividing said casing into separate mixing-chambers, and individual burner-plate having burner-openings therein extending over said mixing-chambers respectively, whereby a combustion-chamber common to, and above both said chambers is provided, said burner-plates closing the bottom of said combustion-chamber, and, through the said burner-openings, establishing communication between said mixing-chambers and said combustion-chamber, independent fuel-

supply systems for said burner-plates respectively comprising a vaporizer disposed above both said burner-plates whereby fuel-oil therein is subjected successively to the flames thereof, and a vaporizer disposed above and wherein fuel-oil is subjected to the flame of but one of said burner-plates, mixing-tubes providing communication between said mixing-chambers respectively and the atmosphere, connections providing communication between each of said vaporizers and a source of oil-supply, and discharging vapors therefrom into said mixing-chambers respectively through said mixing-tubes, and means whereby the fuel-supply for each said burner-plate is controlled independently of the other.

In witness whereof I have hereunto affixed my signature, this 1st day of October, 1902, in the presence of two witnesses,

JOHN N. LEACH.
